(57) **CLAIM**

We claim the ornamental design for a monitoring camera, as shown and described.

DESCRIPTION

FIG. 1 is a perspective view of a monitoring camera; FIG. 2 is a front elevational view of the monitoring camera; FIG. 3 is a rear elevational view of the monitoring camera; FIG. 4 is a left side elevational view of the monitoring camera; FIG. 5 is a right side elevational view of the monitoring camera;

FIG. 6 is a top plan view of the monitoring camera; and, FIG. 7 is a bottom plan view of the monitoring camera.

The portions of the camera in broken lines are shown to illustrate environment only and form no part of the claimed design.
